UNITED STATES PATENT OFFICE.

FREDERICK H. JONES, OF WAKEFIELD, MASSACHUSETTS.

DESIGN FOR A SYRINGE-NOZZLE.

SPECIFICATION forming part of Design No. 32,276, dated February 27, 1900.

Application filed January 31, 1900. Serial No. 3,526. Term of patent 14 years.

To all whom it may concern:

Be it known that I, FREDERICK H. JONES, a citizen of the United States, residing in Wakefield, county of Middlesex, and State of Massachusetts, have invented and produced a new and original Design for Syringe-Nozzles, of which the following is a specification, reference being made to the accompanying drawing, forming a part thereof.

o The drawing shows my newly-designed syringe-nozzle.

The leading or material feature of my design consists in a syringe-nozzle provided with a cylindrical body having a spherical boss at one end and having a number of grooves extended longitudinally for a short distance along said cylindrical body adjacent said spherical boss and also provided with perforations at the base of said spherical projection disposed opposite said grooves and with perforations around said cylindrical body ad-

jacent said spherical boss disposed between said grooves.

a represents the cylindrical body; *b*, a spherical boss at the end thereof; *c*, grooves extended longitudinally in said cylindrical body adjacent said boss; *d*, perforations at the base of said spherical boss disposed opposite said grooves *c*, and *e* perforations at the end of said cylindrical body disposed between said grooves *c*.

I claim—

The design for syringe-nozzle herein shown and described.

In testimony whereof I have signed my name to this specification in the presence of two subscribing witnesses.

FREDERICK H. JONES.

Witnesses:

B. J. NOYES,
J. L. HUTCHINSON.
